Primary Examiner — Catherine Tuttle(57) **CLAIM**

The ornamental design for a dispenser housing, as shown and described.

DESCRIPTION

FIG. 1 is an isometric view showing our new design for a dispenser housing from the top, front and left side;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines are included for the purpose of illustrating portions of the dispenser housing that form no part of the claimed design.
